BACKING PLATE FOR DOOR AND DRAWER PULLS AND THE LIKE

Donald Albert Winton, Pasadena, Calif., assignor to
Hyer Hardware Mfg. Co., Anaheim, Calif., a corpora-
tion of California

Filed Apr. 7, 1969, Ser. No. 16,588

Term of patent 14 years

Int. Cl. D8—03

U.S. Cl. D8—179

FIG. 1.

FIG. 2.

FIG. 3.

FIG. 1 is a front elevation of a backing plate for door and drawer pulls and the like showing my new design; FIG. 2 is a side elevation thereof; and

FIG. 3 is an end elevation thereof.

I claim:

The ornamental design for a backing plate for door and drawer pulls and the like, as shown.
